UNITED STATES PATENT OFFICE.

FERDINAND HACK, OF CHICAGO, ILLINOIS.

BRIDGE-GATE.

SPECIFICATION forming part of Letters Patent No. 332,077, dated December 8, 1885.

Application filed February 2, 1885. Serial No. 154,777. (No model.)

To all whom it may concern:

Be it known that I, FERDINAND HACK, a citizen of the United States, residing in Chicago, county of Cook, and State of Illinois, 5 have invented certain new and useful Improvements in Bridge-Gates, of which the following is a specification.

This invention relates to improvements in bridge-gates especially designed for pivot- 10 bridges automatically actuating the gate to close it when the bridge opens, and open the gate when the bridge closes.

The objects of this invention are to have 15 the gate open and close by a vertical movement, and when closed to constitute a portion of the sidewalk and road approach to the bridge, and to have such a gate automatically closed, and maintained in that position by the closing of the bridge operating against 20 the force of weights tending to open the gates. Further objects are to utilize the double inclined abutment-block of a pivot-bridge as a means for connecting the bridge with and actuating the gate to close it, and to 25 have such connections between the bridge and gate that the gate will be closed at substantially the moment the bridge begins to open, and the gate not opened until the bridge is substantially closed. A further object is to 30 avoid the employment of gear and ratchet mechanism, and the consequent liability of the parts actuating the gate to become clogged with dirt, requiring an increase of power to 35 actuate the gate and involving a liability of breaking and unfitting the connections for use. I attain these objects by devices illustrated in the accompanying drawings, in which—

Figure 1 represents a side elevation of my 40 gate and its actuating devices held in an open position by the bridge, dotted lines indicating the position of the side lever connections and weights when the gate is open; Fig. 2, a front elevation of the same with the bridge removed, dotted lines indicating the position 45 of the levers and gate when the latter is closed; Fig. 3, a central longitudinal section through the bridge approach; Fig. 4, a front elevation showing another form of my invention.

Similar letters of reference indicate the 50 same parts in the several figures of the drawings.

The gate A is preferably composed of top

bar, a, and bottom bar, b, connected by slats, but in any case, whether open or solid, it should have slots c for the free passage of the 55 ordinary sills, d, of the bridge approach, which at the same time serve to steady the gate in its up and down movement, though to attain this object in a more effective degree rods e e 60 may extend vertically through the gate and be secured at their upper ends in a hand rail or projection, f f, (see Fig. 4,) secured thereon, and at their lower end these rods may be secured in some rigid portion of the superstructure of the abutment. 65

For the purpose of automatically closing—that is to say, elevating—the gate a pulley, e', secured to some fixed portion of the bridge approach above the bottom of the gate when in an elevated condition—as, for instance, the 70 hand-rail (see Fig. 3) and a cord, e'', secured to the gate and passing over the pulley, and having on its end a weight, e'', may be employed.

The upper portion or top rail of the gate, 75 when closed, is constructed so as to form and constitute a part of the flooring of the bridge approach, and the height of the gate is sufficient to render it an effective guard. In this 80 connection it may be observed that for ordinary purposes all that portion of the gate below the top rail or bar may be omitted without an essential departure from my invention.

Pivoted on each end of the gate-top rail, and preferably outside of the hand-rail, are levers 85 B, to the upwardly-projecting ends of which are pivoted one end of levers C, pivoted toward their rear end to the hand-rail, and having on their extremities weights D, which are auxiliary to the weights d in opening the gate. 90 To this lever, forward of its rear pivot, is pivoted a lever, E, which in turn is pivoted near the forward end of a lever, F, the rear end of which is pivoted to a standard at a point in a plane below the rear pivot of the lever C. 95 Lever F is connected by a link, G, to a lever, H, which is pivoted at a point intermediate its ends to a sill, H', supported on standards H'', rising above the abutment, the sill H' being in a plane below the flooring of the bridge 100 approach. The inner ends of levers H are pivoted in elongated slots in the ends of levers I, which about their centers of length are pivoted to the sill H', and at their inner ends

these levers I are pivoted to the double-inclined abutment-block J, which in ordinary bridge structures is stationary and fixed on the abutment, to take up the sag of the bridge, 5 but in the present instance is suspended by the levers I, the sag of the bridge being principally taken up by rollers K, beyond each end of the block, and fixed to a stationary part of the bridge approach.

10 The slotted connection between the levers H and I serves the purpose of taking up lost motion and enabling the levers to freely operate, the arrangement of the levers being such that a depression of the abutment-block 15 one foot will cause the gate to rise about four or five feet above its lowest position.

By having a yielding connection for and between the abutment-block and the gate there is a certainty of operation of the gate, and 20 that it will close the moment the bridge begins to open and not open until the bridge is completely closed. This will be better understood when it is remembered that the entire length of the abutment-block need not be more than 25 about two feet, and that it is not engaged by the bridge directly, but by a similar block, L, (see Fig. 1,) secured on the under side of and at the middle portion of the end of the bridge, with its inclined sides projecting downwardly.

30 Instead of employing the side levers, B, C, E, and F, and weights D, these may be dispensed and, as shown in Fig. 4, the levers H be connected by a link, M, directly with the top bar or rail of the gate, weights d of course 35 being employed to automatically close the gate when the abutment-block is released from the bridge.

So far as I am aware an abutment-block yielding independently of the gate, by means 40 of which and a lever-connection a gate is automatically opened by the bridge, is new, and

I therefore do not limit myself to the special connections shown and described between the block and the gate, for it may be used in connection with other forms of levers or gear and 45 rack devices without a substantial departure from these special features of my invention, whereby I am enabled to utilize this block when not forming a part of the gate, and thereby secure the opening and closing of 50 the gate at the special time above referred to.

Having described my invention, what I claim, and desire to secure by Letters Patent, is—

1. A vertically-sliding gate, the yielding 55 abutment-block separate from said gate, and a lever-connection between said gate and block, in combination with a weight connected with and overcoming the gravity of said gate to elevate it above the bridge approach, substantially as described.

2. The gate provided with the elongated slot c and a top rail constituting a portion of the bridge approach when the bridge is closed, in combination with the abutment-block, the 65 levers H and I, pivoted thereto and to each other, and a link-connection between said levers and the gate, substantially as described.

3. The combination of the bridge approach having its floor slotted at a point removed 70 from its end, the vertical-sliding gate moving in said slot, and when lowered forming a part of said floor, the yielding abutment-block separate from said gate, a yielding connection between the gate and block, connected with the 75 gate and overcoming the gravity thereof to elevate it above the bridge approach or floor, as and for the purpose set forth.

FERDINAND HACK.
